UNITED STATES PATENT OFFICE

ANDREW MORRISON, OF PITTSBURG, PENNSYLVANIA.

INSULATED RAIL-JOINT.

No. 894,032.

Specification of Letters Patent. Patented July 21, 1908.

Application filed January 23, 1908. Serial No. 412,270.

To all whom it may concern:

Be it known that I, ANDREW MORRISON, of Pittsburgh, in the county of Allegheny and State of Pennsylvania, have invented a new and useful Improvement in Insulated Rail-Joints, of which the following is a full, clear, and exact description, reference being had to the accompanying drawings, forming part of this specification, in which—

10 Figures 1 and 2 are sectional views of rail joints embodying my invention.

My invention has relation to the class of insulated rail joints, relating more particularly to the manner of insulating the same, 15 the invention being designed to reduce the amount of insulation required.

It is well known that in insulated rail joints, the greatest wear upon the insulation occurs upon that portion thereof which is interposed between the upper edges of the splice bars and the under sides of the adjacent rails, owing to the severe pounding which these portions of the insulation receive. In accordance with my invention, I 25 make the insulation for this portion of the joint in separate pieces which are so arranged that they can be reversed edge for edge, thereby practically doubling the life of the insulation.

30 Referring to the drawing, the numeral 2 designates the rail; 3 the splice bars; 4 one of the joint bolts.

5 and 6 designate the insulation, which is interposed between the joint bars and rails. 35 The insulating pieces or strips 5 which are interposed between the upper edges of the splice bars and the under sides of the heads of the rails are made in a separate piece from the portions 6, which are interposed between 40 the lower portions of the splice bars and the upper surfaces of the base flanges of the rails, being in this respect similar to the mode of insulation employed in my Patent Number 875,203, dated December 31, 1907. In accordance with my present invention, however, the insulating strips 5 are so made that they can be reversed edge for edge so that the depending portions 5^a thereof, which lie against the upper portions of the webs of the 50 rails, can take the place of the portions 5. In this manner, when the portions 5 become

so cut or worn as to be no longer effective, the pieces can be readily reversed and thus practically double their life. This feature, together with the fact that there is no useless 55 insulation used adjacent the middle portion of the webs of the rails very largely decreases the cost of the joints.

The form of invention shown in Fig. 2 differs from that shown in Fig. 1, only in that 60 instead of employing an insulating sleeve 7, where the bolt 4 passes through the web of the rail, an insulating sleeve 8 is employed around the bolt, where it passes through one of the splice bars. This enables the depending portions of the insulation to be made somewhat longer and to come in contact with the bolts, this form, however, being equally reversible edge for edge.

My invention is obviously applicable to 70 joint bars of various other sections than those shown, being in fact independent of any particular form of the joint.

I claim:

1. In an insulated rail joint, an insulating 75 strip interposed between the upper edge of the splice bar and the under side of the head of the rail and having a free portion extending downwardly between the splice bar and the web of the rail, said strip being reversible 80 edge for edge, substantially as described.

2. In an insulated rail joint, an insulating strip interposed between the upper edge of the splice bar and the under side of the head of the rail and having a free portion extending 85 downwardly between the splice bar and the web of the rail, said strip being separate from the insulation which is placed between the lower portion of the splice bar and the base of the rail, and reversible edge for edge, 90 substantially as described.

3. In an insulated rail joint, an insulating strip adapted for use between the upper edge of a splice bar and the under side of the head of a rail, said strip having two portions at an 95 angle to each other and of substantially the same length and shape whereby the strip may be used reversibly, substantially as described.

4. In an insulated rail joint, an insulating 100 strip interposed between the upper edge of the splice bar and the under side of the head

of the rail, said strip having two portions of substantially the same length and shape, one of said portions being under compression between the head of the rail and the splice bar, 5 and the other portion being free and not under compression, said strip being reversible edge for edge whereby the portion which has been free and without compression may be

substituted for the part which has been under compression, substantially as described. 10

In testimony whereof, I have hereunto set my hand.

ANDREW MORRISON.
